BAG OR SACK

Joseph D. Cramer, Goshen, Ind., assignor to The Chase Bag Company, New York, N. Y., a corporation of Delaware

Application October 6, 1934, Serial No. 747,184

3 Claims. (Cl. 150—1)

My invention relates to bags or sacks and is an improvement pertaining more particularly to lined heavy duty bags in which the body of the bag is composed of an outer covering and an inner preferably air-tight and liquid tight one way stretchable lining. The outer covering of such bags is ordinarily made of textile fabric such as burlap to withstand rough handling. The inner lining consists of a sheet or sheets of paper or other similar material, creped transversely to yield without cracking, when the bag is folded or otherwise strained, and while ordinarily connected to the outer covering by a layer of waterproof binder such as asphaltum, the liner 10 may be loosely arranged within the fabric backing.

Bags of the kind referred to are made from tube sections of this composite or multi-ply material, formed in tubing machines of old and well known construction. These machines embody tube-forming devices through which the material is drawn under a pulling tension by means of superposed draw rollers which frictionally engage the formed tube for further advancement and also to flatten same. This conventional mode of making the bags seems to weaken the folded areas of the liner as indicated by the high percentage of liners which rupture at these particular areas. It has been proposed to overcome the above defects by employing so called double stretch liners, made from paper creped or wrinkled in two substantially rectangularly related directions in contradistinction to paper liners such as described as being creped transversely to permit of stretching longitudinally of the bag. However the results obtained with so-called double stretch liners likewise have not been satisfactory.

Having in mind the above defects in bags of the type referred to, it is the primary object of my invention to provide a paper-lined burlap bag with a lining strengthened and reenforced at its bent or folded areas, so as to obviate or materially reduce the high percentage of breakage of these areas.

The reenforced areas of the lining must of course yield to stresses incident to rough handling, etc. and therefore it is another object of my invention to provide yieldable or resilient re-enforcing means capable of stretching with the folded areas of the lining.

To obtain these objects, I have devised a paper-lined burlap bag in which the folded areas of the lining are covered with a film of a yielding or elastic cement, such as latex or processed rubber.

This cement film reenforces the weakened areas and has a shock-absorbing and dampening action so that certain stresses and shocks are absorbed, and breakage of the lining at the folds prevented.

Preferably the cement film or coating is applied by spreading the cementitious liquid upon the lining and then covering the same with a paper strip or a layer of powdered material so as to permit of continuous manufacturing operations without danger of cementing the inner walls of the lining together. However except for convenience in manufacturing and to facilitate stacking the bags before the cement has dried, the use of powder or other covering for the latex is not necessary.

The novel features that I consider characteristic of my invention are set forth with particularity in the appended claims. The invention itself, however will best be understood from the following description of a specific embodiment when read in connection with the accompanying drawing, in which

Figure 1 is a plan view of a paper-lined burlap bag having the reinforcing latex film applied to the folded areas of the paper lining, the different layers of the outer covering and inner lining being partly broken away to disclose the construction of the bag, its seam and the latex film.

Figure 2 is an enlarged transversal sectional view on line 2—2 of Figure 1, the bag being broken away intermediate its width.

Figure 3 is an enlarged longitudinal sectional view on line 3—3 of Figure 2; and

Figure 4 is an enlarged fragmentary sectional view similar to Figure 3 of a bag in which the reenforcing of the bent area of the lining is effected by means of an uncovered yielding cementitious film.

In the preferred embodiment of my invention shown in Figures 1 to 3 of the drawing, the bag 2 is formed from a composite sheet including an outer layer of woven fabric 3, such as burlap. This outer layer carries an inner lining member 4 fastened thereto by means of a layer of waterproof binder 5. The liner 4 preferably consists of two smooth sheets of tough thin preferably transversely creped paper 6, secured together by means of an interposed layer of waterproof binder 7, such as asphaltum.

The web of material, comprising the outer layer 3 and the lining member 4 secured thereto, is folded at 8 and 9 and joined by an overlapping seam 10 arranged in the middle of the seamed

side wall 11 of the bag. A very tight seam is assured by overlapping the edges 12, 12' of the outer fabric layer 3 with respect to each other, and by overlapping the edges 14, 14' of the lining member, all as clearly disclosed in Figures 1 and 2. These overlapping portions are pasted together by any suitable adhesive such as waterproof binder 5. To facilitate the overlapping of the layer 3 and the lining member 4, the layer 3 and the lining member 4 are laterally offset with respect to each other, that is, one edge of the fabric extends beyond the corresponding edge of the liner 4 to form an unlined marginal portion 15. It will also be noted that one of the paper sheets 6, preferably the outer one, is somewhat wider than its companion sheet, and is offset transversely with relation thereto thus providing extended portions or strips 17 on the respective sheets which project beyond the corresponding edges 16 of the other sheets and beyond the edges of the binder between these sheets. The thickness of the seam is thus reduced and a substantially air-tight and water-tight seal is had. The extended edges 17 and other overlapping parts are pasted to the opposing parts by any suitable waterproof adhesive of sufficient strength.

The bottom edge of the thus formed tube is seamed by a binding strip 18, consisting of two layers of woven fabric 19, 20 secured to each other by means of a waterproof binder 21, such as an asphaltic material. Preferably as shown, a sheet of tough paper 22 is inserted between the outer fabric layer 19 and the binder 21 to prevent the latter from being pressed through the texture of the outer layer 19, the paper sheet 22 being suitably pasted or otherwise secured to the layer 19. The bag when filled is closed at its top by a binding strip 18' as indicated in dotted lines in Figure 1.

The folded or bent portions 23 of the lining members 4 (only one of which is shown) are provided with thin, yielding cementitious films 24, which are preferably formed by spreading a solution of latex, processed rubber or other elastic cementitious material over and adjacent to the folded areas. The films extend from the top to the bottom of the bag, and are preferably protected by strips of preferably transversely creped paper 25, to permit of continuous manufacturing of the tube sections in a tubing machine of common construction, without danger of the opposing areas 23 sticking to each other. Numerous comparative tests have proven that the paper strips 25, do not fortify the folded areas against breakage to any appreciable degree, and consequently any suitable covering medium for the

resilient film may be employed, such as talcum or other powdered material.

The films 24 yield under the abrupt and excessive stresses to which the liner is subjected, and take up part of these stresses by their yielding and absorbing action. This action may best be compared with that of a shock absorber.

As the creped paper strips 25 have little or no reenforcing effect on the areas 23 it is obvious that these strips can readily be omitted without danger of liner breakage or manufacturing difficulties, if means is provided for quickly drying the films, or otherwise preventing sticking of the lining members, at the reenforced areas 23. Such a simplified structure is disclosed in Figure 15 4 of the drawing, in which the latex film 24 is openly exposed.

Air and water-tight lined burlap bags reenforced in the manner described will stand excessive wear and abuse even though the sheets 6 20 of the lining are creped and stretchable in one direction only, and have also proven to be far superior to bags in which the lining is creped and/or folded or corrugated in two directions.

Although I have shown and described certain specific embodiments of my invention, I am fully aware that many modifications thereof are possible. My invention, therefore, is not to be restricted except insofar as is necessitated by the prior art and by the spirit of the appended claims.

Having thus described my invention, what I claim is:

1. In a flat bag, a creped paper lining folded at the edges of the bag, thin films of latex extending lengthwise of the folded areas at a right-angle to the crepes from top to the bottom of said lining and creped paper strips for covering and protecting said film, said strips being held in place by the adhesive action of said films. 40

2. A doubled walled bag formed of textile fabric and creped paper lining secured thereto by a waterproof binder uniting said fabric and paper over their entire opposed surfaces, folded areas in said bag, and thin films of an elastic adhesive material lengthwise of the folds of said paper lining for reenforcing the folded areas thereof, and protective means covering said elastic adhesive material.

3. A double walled bag formed of textile fabric, and a creped paper lining secured thereto by a waterproof binder uniting said fabric and paper over their entire opposed surfaces, thin films of latex lengthwise of the folds of said paper lining and at a right-angle to the crepes thereof for reenforcing the folded areas of said lining, and means for covering said films.

JOSEPH D. CRAMER.
